UNITED STATES PATENT OFFICE.

FRANK PETERHANS, OF NEW YORK, N. Y.

MACHINE FOR PLUCKING BEAVER AND OTHER SKINS.

SPECIFICATION forming part of Letters Patent No. 331,906, dated December 8, 1885.

Application filed June 21, 1884. Serial No. 135,616. (No model.)

To all whom it may concern:

Be it known that I, FRANK PETERHANS, of the city, county, and State of New York, have invented certain new and useful Improvements in Machines for Plucking Beaver and other Skins, of which the following is a specification.

The skins of beavers, seals, and other amphibious animals have long glossy hair or bristles, the so-called "water-hair," which covers the soft fine hair or wool that forms, after dressing, the main attraction of the same. All these skins have to be freed of the water-hair before they can be dyed and finished for use.

Different machines have heretofore been devised for the purpose of clipping the water-hair of beaver, seal, or other skins, in which a bellows or other air-forcing apparatus is used in connection with means for stretching and feeding the skin, means to retain the fine hair or wool, and means for cutting off the stiff projecting bristles.

The object of this invention is to furnish an improved machine by which the thick bristles or water-hair of the skins are removed in a rapid, uniform, and reliable manner by plucking without the use of an air-forcing apparatus.

In the accompanying drawings, Figure 1 represents a side elevation of my improved machine for plucking beaver and other skins. Fig. 2 is a vertical transverse section of the same on line *x x*, Fig. 1. Figs. 3, 4, and 5 are detail vertical transverse sections of the working parts drawn on a large scale and shown in different positions, so as to illustrate the method of plucking the bristles. Fig. 6 is a detail vertical transverse section on line *y y*, Fig. 4. Figs. 7 and 8 are details of a spring-clamp for stretching the skin, showing it respectively in open and closed position, and Fig. 9 is a detail side view of the clamp shown in Figs. 7 and 8.

Similar letters of reference indicate corresponding parts.

Referring to the drawings, A represents the supporting-frame of my improved machine for plucking beaver and other skins. A knife-edged bar, B, extends transversely from one end of the frame to the other and is rigidly

secured thereto. Over the knife-edged bar B the skin to be plucked is tightly stretched by suitable means, those shown in the drawings consisting of straps *a a*, that are attached to a roller, C, and provided at their free ends with spring-clamps *b*, the fulcrumed and serrated jaws *b' b'*, which are closed by links *b²*, that are connected to the straps *a a*, as shown in Figs. 7, 8, and 9. The opposite end of the skin is also attached to spring-clamps *b*, which are attached by short straps *a'* to a fixed transverse bar, *a²*, as shown clearly in Fig. 2. The links *b²* of the clamps *b* open or close the jaws *b' b'* by means of an anti-friction roller, *b³*, that acts on the smooth levers of the jaws *b' b'*, as shown in Figs. 7 and 8. The proper tension of the skin is imparted by a weighted transverse roller, D, the weight *D'* of which is hung by pivot-links *d d* below the roller, as shown in Figs. 1 and 2. The skin is intermittently wound up on the roller C by means of a pawl, *e*, and ratchet-wheel *e'*, the pawl *e* being pivoted to the upper end of a fulcrumed lever, *e²*, the lower cam-shaped end of which is held by a spiral spring, *e³*, in contact with an anti-friction roller, *e⁴*, of a treadle, E. The pawl *e* is held in engagement with the ratchet-wheel *e'* by a spring, *e⁵*. A check-pawl, *e⁶*, holds the ratchet-wheel *e'* in position during the receding motion of the pawl *e*. The depression of the treadle E causes the disengagement of the pawl *e* from the teeth of the ratchet-wheel, while the release of the treadle produces the forward motion of the fulcrumed lever *e²*, so that the pawl *e* re-engages the teeth of the ratchet-wheel *e'* and turns the roller C for the required distance. By the action of the treadle E on the pawl-and-ratchet mechanism the gradual winding up of the skin on the roller C is produced and the skin drawn gradually over the knife-edged bar B, the skin being kept in tightly-stretched condition by the weighted roller D. The treadle E is further connected by rods *E'* with slide-plates *E²*, which are guided by oblong slots *f* along the fixed bar B, and by narrower slots *f'* at the upper end along fixed guide-pins *f²*, as shown clearly in Figs. 3, 4, and 5. The upper ends of the slide-plates *E²* are connected to straps *g*, which are passed over rollers *g'* at the upper part of the supporting-frame A and connected

by springs g^2 to fixed points of the frame A. The downward motion of the treadle E lowers the slide-plates E² against the tension of the springs, and on the release of the treadle said 5 springs cause the raising of the treadle and of the slide-plates E².

On each slide-plate E² is supported a second auxiliary slide plate, E³, which is connected to the opposite slide-plate E² by transverse 10 pieces E⁴, one at each side of the fixed knife-edged bar B. The auxiliary slide-plates E³ are guided on raised flanges f³, extending around the sides of the slots f of the main slide-plates E². The auxiliary slide-plates E³ 15 are connected by spiral springs f⁴ to the main slide-plates E², as shown in Figs. 3, 4, and 5.

On the transverse connecting-pieces E⁴ is supported a horizontal guard-frame, F, that extends across the knife-edged bar B, and 20 which is provided with transverse slots, through which the stiff bristles or water-hair of the skin are projected when the guard-frame is lowered. The bristles or water-hair are passed through the slots of the guard-frame 25 F by the action of an oscillating comb, F', the tines of which pass close to that part of the skin above the knife-edged bar, so that the bristles are combed up and carried along in upward direction through the slots of the 30 guard-frame F. Simultaneously therewith the guard-frame F is lowered by the action of the treadle until it arrives close to the knife-edged bar B, as shown in Fig. 4. The motion of the auxiliary slide-plate E³ is next arrested by 35 the raised flange or rim f³, while the downward motion of the main slide-plates E² is continued. The tines of the auxiliary comb F' are moved upward above the guard-frame F with the bristles, the comb F' being then 40 moved sidewise, as shown in Fig. 5, so as to be out of the way of the plucking-jaws G, which are pivoted to the main slide-plates E² vertically above the bar B. The lateral motion of the comb F' is accomplished by a ful- 45 crumed lever, g, the pointed end of which engages a tapering recess, g', of the fixed bar B. The outer end of the lever g is connected by a pivot-rod, g², to a short backwardly-extending crank-arm, g³, of the auxiliary comb F'. 50 The comb F' is pivoted at both ends to slots g⁴ of the auxiliary slide-plates E³, and engaged by the slotted upper ends of pivoted and spring-actuated pieces g⁵. A fixed anti-friction roller, g⁶, is arranged on the end standards 55 of the frame A sidewise of the slotted piece g⁵, which latter is pressed by its spring g⁷ against said anti-friction roller g⁶. Each main slide-plate E² is guided by a vertical slot, g⁸, on the roller g⁶, the slot controlling the down- 60 ward motion of the slide-plate E². The cam-shaped edge of the oscillating piece g⁵ moves along the roller g⁶ by the downward motion of the main slide-plate E², and serves, in connection with the knife-edged bar B and the levers 65 g and links g', first to raise the tines of the auxiliary comb through the slots of the guard-

frame F and then to move the auxiliary comb F' sidewise in the slots g⁴ of the auxiliary slide-plates E³, as shown, respectively, in Figs. 3, 4, and 5. The oscillating and lateral motions 70 of the auxiliary guard-comb F' take place during the downward motion of the treadle E, which also lowers the main and auxiliary slide-plates E² and the guard-frame F until the latter arrives at a point just above the 75 edge of the fixed bar B. While the guard-frame F is retained in this position the main slide-plates E² continue to move downward farther, so as to stretch the spiral springs f⁴ and keep thereby the auxiliary plates E³ and 80 the guard-frame F in position until the main slide-plates E² and the guard-comb F' have completed their motion. The plucking-jaws G G are lowered with the main slide-plates E² until they arrive at a point just above 85 the guard-frame F. The jaws G G are held apart by means of spiral springs h h, interposed between the same. One of the jaws G is provided with an upwardly-extending arm or arms, G', which are connected at their 90 upper ends by spiral springs m to the main slide-plates E², said arms abutting when in normal position by the action of the spiral springs m against fixed stops m'. The other jaw G is provided with a central forward-ex- 95 tending lever, G², which is taken hold of by the workman for the purpose of operating the jaws. Both levers are provided at their lower edges with serrated steel faces h' h', which firmly clamp the stiff bristles projecting above 100 the guard-frame F when the plucking-jaws are closed by pressure on the lever G². The pressure exerted by the lever G² upon one jaw G closes the serrated steel faces of the jaws, after which a quick jerky motion is imparted 105 to the lever G², which, in connection with the weight of the jaws and the tension exerted by the springs m, causes the sudden plucking of the bristles from the skin. The jaws are then released and returned into vertical position, the 110 treadle E being released at the same time, so that the main slide-plates E² and the auxiliary slide-plates E³ are returned by the springs g² into their normal positions. The auxiliary guard-comb F' is also returned into its first 115 position. (Shown in Fig. 3.) The upward motion of the treadle causes the turning of the winding-up roller by the pawl-and-ratchet mechanism described, so that the skin is fed forward over the knife-edged bar and the next 120 adjoining portion, and ready to be exposed to the action of the plucking devices. The treadle is again lowered and the guard-frame placed above the next adjoining narrow strip of skin on the knife-edged bar. The auxiliary 125 guard-comb is moved upward and sidewise of the same, and the plucking-jaws are lowered so as to take hold of the bristles and pull the same out of the skin. The operation described is repeated until the entire skin is 130 completely plucked. The operation of pulling or plucking the water-hair from the skins

is thus accomplished in a quick and reliable manner without the use of an air-draft from a bellows or other air-forcing apparatus.

The machine is specially adapted for plucking the water-hairs of beaver and seal skins and in all such other cases in which the plucking of the bristles is preferable to the mere clipping or cutting of the same close to the skin itself. By plucking the bristles the skins are rendered softer and smoother, as they are pulled out at their roots and no short portions of the bristles left standing in the fine hair or wool of the skins, as is the case when clipping-knives have been used.

15 I am aware that knife-edge bars, reciprocating plucking-jaws, and oscillating combs are not new broadly.

Having thus described my invention, I claim as new and desire to secure by Letters Patent—

20 1. The combination of a knife-edge bar over which the skins are stretched and fed, a vertically-reciprocating slotted guard-frame, an oscillating laterally-reciprocating guard-comb, and oscillating and vertically-reciprocating plucking-jaws, substantially as described.

25 2. The combination of a supporting-frame, a knife-edge bar over which the skins are stretched and fed, a vertically-reciprocating main plate, oscillating jaws pivoted to said main plate, an auxiliary vertically-reciprocating plate provided with horizontal slots, a horizontal slotted guard-frame attached to said auxiliary plate, stops for arresting the downward movement of the auxiliary plate, before the downward movement of the main plate is completed, an oscillating comb supported in said slots of the auxiliary plate and provided with a backwardly-projecting 35 crank-arm, a lever pivoted to said main slide-plate, one end of which extends between fixed stops, and a link connecting the end of said lever with the crank-arm of said comb, whereby the latter is oscillated during the downward movement of said main plate, substantially as described.

40 3. The combination of a supporting-frame, a knife-edge bar over which the skins are stretched and fed, a vertically-reciprocating main plate, oscillating jaws pivoted to said

main plate, an auxiliary vertically-reciprocating plate provided with horizontal slots, a horizontal slotted guard-frame attached to said auxiliary plate, stops for arresting the downward movement of the auxiliary plate 55 before the downward movement of the main plate is completed, an oscillating comb supported in said slots and provided with a backwardly-projecting crank-arm, a slotted cam-lever engaging said comb and pivoted to 60 said main plate, and a fixed anti-friction roller and spring for actuating said lever to move said comb laterally within said horizontal slot of the auxiliary plate during the downward movement of the main plate, substantially as described.

4. The combination of a supporting-frame, a knife-edge bar over which the skins are stretched and fed, a vertically-reciprocating main plate, oscillating jaws pivoted to said 7c main plate, an auxiliary vertically-reciprocating plate provided with horizontal slots, a horizontal slotted guard-frame attached to said auxiliary plate, stops for arresting the downward movement of the auxiliary plate 75 before the downward movement of the main plate is completed, an oscillating comb supported in said slots and provided with a backwardly-projecting crank-arm, a lever pivoted to said main slide-plate, one end of 80 which extends between fixed stops, and a link connecting the end of said lever with the crank-arm of said comb, whereby the latter is oscillated during the downward movement of said main plate, a slotted cam-lever 85 engaging said comb and pivoted to said main plate, and a fixed anti-friction roller and spring for actuating said lever to move said comb laterally within said horizontal slot of the auxiliary plate during the downward 9c movement of the main plate, substantially as described.

In testimony that I claim the foregoing as my invention I have signed my name in presence of two subscribing witnesses.

FRANK PETERHANS.
